ABSTRACT OF THE DISCLOSURE

The specification discloses scrubber and dryer apparatus particularly useful in conjunction with municipal incinerators for the removal of fly ash from the gaseous combustion products. The scrubber comprises a chamber having surface-porous castable refractory piers in several rows, each row of which is staggered with respect to the preceding row. In one embodiment, the chamber widens from front to rear and the spacing between adjacent piers in each succeeding row decreases. The ash is trapped by impingement on a continuous curtain of water disposed at the inlet of the scrubber just upstream of the piers. Water to form the curtain is pumped into a manifold set transverse to the chamber inlet and having a slot therein. The gases carry the water downstream in relatively large droplets to impinge on the piers where the water and trapped ash flows off. The dryer chamber comprises a deflecting arch having openings therein that directs the gases against the chamber walls whereby water is stripped therefrom. The gases, after passing through the scrubber and then the dryer, are exhausted as substantially clear air, having a tested dust loading value of from 54 to 68% below the commonly accepted standard of 0.85 lb. dust/1000 lbs. flue gas. The scrubber and dryer can be used for other gases, e.g. for trapping SO₂ in the production of sulfuric acid. A method of scrubbing gases is disclosed.

This application is a continuation-in-part of application Ser. No. 527,368 filed Feb. 14, 1966, and now abandoned.

Field

This invention relates to a scrubber-dryer device for industrial gases, and more particularly to a scrubber-dryer in combination with an incinerator that significantly reduces air pollution. The application is also directed to a method of treating gases such as a result from incineration of household and industrial waste, garbage and the like which results in relatively clean products of combustion being discharged from the incinerator as compared with the discharge from conventional chimney or stack-type refuse burners by reason of the removal of a greater proportion of fly ash.

Background

Spray chambers and conventional gas scrubbers have long been used in combination with incinerators and the like in order to wash the gases and remove fly ash therefrom in an attempt to prevent pollution of the air by the exhaust discharge from such incinerators. A typical municipal incinerator of the above type is illustrated in U.S. Patent 3,031,981 wherein a spray chamber is used to trap the fly ash before exhausting to the atmosphere. The typical plant has a primary combustion chamber, a secondary chamber that ordinarily operates both as a fly ash settling chamber and a secondary combustion zone, a spray chamber in communication therewith and an exhaust stack. However, actual experience has shown that spray chambers have not been satisfactory in reducing the allowable dust loading of the flue gas to an acceptable

2

level. In view of the recent emphasis on stricter air pollution codes, such operation has become entirely unacceptable.

There are many different codes and limitations on solids emissions being enforced by air pollution agencies throughout the country. The one that has received the widest acceptance up to this time has limited the permissible discharge from incinerators to 0.85 lb. dust per 1000 lbs. flue gas, adjusted to a 50% excess air basis. The second most widely adopted and enforced limitation uses the same dust concentration limitation, but the results are corrected to a 12% carbon dioxide basis. Both of these limitations have their origin in the old Model Smoke Law of the American Society of Mechanical Engineers. In recent years, there has been a definite trend to reduce the permissible level of incinerator particulate emission. Unfortunately, however, there has been little uniformity followed in the method of expressing these limitations as each new code is adopted, and thus incinerators to be nationally acceptable must meet the most stringent code. In test runs on incinerators embodying the scrubber and dryer of this invention, the average of several runs of exit dust loading is between 53.4% and 68.0% below the above-noted most widely accepted exit flue gas dust loading limitation of 0.85 lb. of dust per 1000 lbs. of flue gas, corrected to a 50% excess air basis. In addition, actual test runs show that an incinerator embodying the scrubber and dryer of the present invention achieves even the most stringent requirements (e.g., city of Detroit and State of Florida) for stack exit dust loading, whether expressed in actual gas basis or the less commonly used dry standard cubic foot per minute basis, either corrected to 50% excess air or 12% carbon dioxide and expressed in grains per dry cubic foot or pounds of dust per 1000 lbs. of flue gas.

Conventional multi-wash collectors have been used in combination with incinerators to remove fly ash. Such multi-wash collectors operate by introducing, under force draft, dust, fumes or vapors tangentially through an inlet at the bottom of the silo. A conical bottom creates a vortex which sends the air upwards in a spiraling motion. A washing agent, such as water, is introduced at no head pressure just below an entrainment separator, and the water cascades downwardly evenly over plates carrying collected material to a slurry outlet. Another type of a cascade collector is shown in U.S. Patent 2,585,440. It differs principally from the above multi-wash collector by being of the downdraft type with sprayers above the series of baffles.

However, actual experience shows that such types of cascade collectors have not been satisfactory in reducing incinerator flue gases to permissible levels of dust loading. One of the problems is that the flue gases contain acid forming components which in combination with the water form extremely corrosive conditions that destroy the metal components of such type of collectors. In order to overcome this problem, lime has been added to the water used in such collectors in order to neutralize the acids formed. However, under conditions involving hot gases of up to 1400 to 1800° F. exiting from the primary or secondary chamber of incinerators, the quantities of lime in the water necessary to neutralize the acid components is such that rapid build-up of a deposit on the cascade surfaces, entrainment separators and plates clogs the scrubber to the point of inoperability. The lifetime of such separators is also extremely short and thus economically unfeasible. In addition, the spray or cascade type of collector does not remove the entrained particulate matter from the air to the degree necessary to satisfy minimum requirements for modern day codes.

Typical examples of spray type scrubbers are found in U.S. Patents 2,045,115, 1,952,389, 1,509,475, 3,031,982,

and 2,045,519. Typical problems with such conventional type of spray-type scrubbers have been that the scrubber heads, although they may be recessed in the chamber walls, continuously burn out and become clogged. In addition, those made of metal suffer from the same short lifetime problems as described above with reference to the cascade type of collectors. More seriously, however, is the fact that they do not operate to produce the necessary result, that of removing the air pollutants to an acceptable level.

THE INVENTION

Objects

A major object of this invention is to provide an improved type of scrubber and dryer useful for removing entrained particulate matter and acid forming components from industrial gases, such as flue gases from incinerators, those involved in the production of sulphuric acid, or the like, which scrubber and dryer removes entrained particulate matter and undesirable components to a level below permissible for discharge to the atmosphere as substantially clear air.

It is another object of this invention to utilize such scrubber and dryer in combination with municipal type incinerators in which secondary combustion chambers may be dispensed with, the construction being extremely simple, compact and inexpensive and providing substantial improvements in efficiency whereby the capacity of existing incinerators can be increased.

One object of the invention is to provide an incinerator having a combustion chamber for refuse which is provided with an inlet for refuse dumped from a truck or the like and an outlet leading to a gas scrubber through which the products of combustion flow and from which most of the fly ash is removed, the products of combustion then passing through a drying chamber before being discharged to atmosphere.

Another object is to provide an efficient refuse incinerator which is comparatively inexpensive to construct and economical to operate, and to provide a method of treating refuse which burns a maximum proportion thereof and efficiently removes both dry ashes and fly ash from the combustion chamber before the residual products of combustion are discharged to atmosphere, the design being such that the usual high stack to create draft is not needed, and improved incinerator capacity may be achieved.

An additional object is to provide in combination with the scrubber-dryer a single conveyor to receive water drained from scrubber elements in a chamber of the gas scrubber together with fly ash collected thereby from the products of combustion passing through the gas scrubber and operable to remove sludge from the water whereupon the water can be reused in the gas scrubber.

Another object is to provide pump means to receive water from the sludge conveyor and recirculate it to the gas scrubber, the gas scrubber having a trough receiving such water and provided with a transverse slot at the inlet end of the scrubber chamber from which a curtain of water falls across the inlet, and to provide a series of spaced scrubber elements against which such water is carried by the products of combustion as they pass through the gas scrubber chamber.

Another additional object is to provide the scrubber elements in the form of refractory piers mounted in the gas scrubber chamber, a plurality of rows of the piers being provided and the piers in each successive row being staggered relative to the piers in the preceding row, the spacing between the piers being such as to substantially increase the velocity of the products of combustion as they pass through the gas scrubber chamber.

Another object is to provide means for supplying make-up water to the pump means to compensate for any water that is evaporated during the gas scrubber operation.

Another object is to provide a drying chamber downstream of the gas scrubber which has deflecting means

5 therein for deflecting the products of combustion from the gas scrubber toward the wall of the drying chamber so that any water carried thereby impinges the wall and drains down it and into the sludge conveyor instead of passing out to atmosphere.

Drawings

With these and other objects in view, my invention consists in the construction, arrangement and combination of the various parts of the scrubber and dryer and their combination with an incinerator, and in the steps of my method of treating refuse, whereby the objects above contemplated are attained, as hereinafter more fully set forth, pointed out in my claims and illustrated in detail on the accompanying drawings, wherein:

10 FIG. 1 is a plan view of the reciprocating grate means and an ash conveyor of my incinerator which are disclosed and claimed in my copending application Ser. No. 648,845, filed Nov. 9, 1967, as a division of parent application Ser. No. 527,368 filed Feb. 14, 1966.

15 FIG. 1A is a continuation of FIG. 1 and shows a gas scrubber in horizontal section;

20 FIG. 2 is a vertical sectional view through the portion of my incinerator shown in FIG. 1, FIG. 1 being taken 25 on the line 1—1 of FIG. 2;

25 FIG. 2A is a vertical sectional view through the remaining portion of my incinerator and is a continuation of FIG. 2, FIG. 1A being taken on the line 1A—1A of FIG. 2A;

30 FIG. 3 is a part plan view, part horizontal sectional view taken on the line 3—3 of FIG. 2A;

35 FIG. 4 is an enlarged horizontal sectional view on the line 4—4 of FIG. 3;

40 FIG. 5 is a vertical sectional view on the line 5—5 of FIG. 1, and shows the parts on an enlarged scale;

45 FIG. 6 is a further enlarged detail sectional view of the portion of FIG. 5 shown within the dot-and-dash rectangle 6 thereof;

40 FIG. 7 is a vertical sectional view on the line 7—7 of FIG. 1A showing details of a dry ash conveyor;

50 FIG. 8 is a vertical sectional view similar to a portion at the right hand end of FIG. 2 to show further details of the dry ash conveyor;

55 FIG. 9 is a vertical sectional view on the line 9—9 of FIG. 2 to show details of a rack and pinion drive for grate means of my incinerator;

FIG. 10 is a vertical sectional view of a second embodiment of my incinerator;

50 FIG. 10A is a vertical sectional view of the scrubber-dryer section of the embodiment shown in FIG. 10 taken along a line 10A—10A in FIG. 11; and

55 FIG. 11 is a plan view of the scrubber-dryer section shown along line 11—11 of FIG. 10A.

Detailed description

60 On the accompanying drawings of a single incinerator cell, several areas and dominant parts of the incinerator per se and the scrubber-dryer are designated by reference characters as follows:

CC—Combustion Chamber

GM—Grate Means

AC—Ash Conveyor

GS—Gas Scrubber

SC—Sludge Conveyor

DA—Deflecting Arch

DC—Drying Chamber

65 The combustion chamber CC comprises a floor 10 shown 70 in FIGS. 5, 7 and 8, sidewalls 12 and a top wall 14. The combustion chamber also has a front wall 16 and a rear wall 18, and adjacent the front wall 16 is an inclined wall 20 constituting an inlet chute. The combustion chamber is the primary combustion chamber or first high temperature zone of the incinerator. As shown in FIG. 2, the left

hand end of the combustion chamber is open at 13 above the inclined wall 20 so that refuse trucks can back up to the combustion chamber and discharge their contents down the inclined wall 20 on to the grate means GM, which is shown only schematically in FIG. 10. A second embodiment having a restricted opening 201 formed between depending top baffle 202 and inclined wall 20 is shown in FIG. 10. The incinerator of FIG. 10 may be charged by conveyor 203, or directly from a truck.

The walls 12 and 14 are continuous with portions 12a and 14a at the right hand end in FIGS. 1, 2 and 10 which continue into FIGS. 1A, 2A and 10A to form a baffle chamber or secondary combustion chamber 207. The baffle or bridge wall 18a shown in FIGS. 1 and 2 is an upward extension of the rear wall 18 of the combustion chamber. The bridge wall may be forwardly inclined as shown in FIG. 10. Further downstream is a downwardly extending baffle or drop arch 22 shown in FIGS. 1A, 2A and 10A, against which hot gases (about 1800° F.) impinge. Both the bridge wall and drop arch are upstream from the gas scrubber GS. The chamber 207 may be provided with a sloping floor 24 which continues as at 24a in FIGS. 1A and 2A to form a floor for the gas scrubber GS. Optionally, the gas scrubber floor 24a may be separate as shown in FIG. 10A. The chamber space defined between the bridge wall and scrubber inlet downstream of the drop arch is the second high temperature zone. In an incinerator utilizing the scrubber-dryer of this invention this zone does not act as a settling chamber. Prior art settling chambers, ordinarily of size 12 feet wide by 27 feet high by 35 feet long for a 2-cell incinerator, can be eliminated in my invention since the scrubber-dryer can handle all the fly ash without preliminary settling of large ash.

The floor 24a, sidewalls 12b and a top wall 14b which is an extension of the top wall 14a provide a gas scrubber chamber. The details of one embodiment are shown in FIGS. 1A and 2A. In this chamber a series of vertical piers 28 constitute scrubber elements which, as shown in FIGS. 1A and 10A are arranged in rows and staggered relative to each other in successive rows to provide a tortuous path for the products of combustion and fly ash passing through the gas scrubber GS. These piers are spaced so that the area between them for the flow of combustion gases is reduced to about one-third the area within the baffle chamber 12a, 14a, 24, so that the velocity of combustion gases and fly ash through the gas scrubber is increased for efficiency of the gas scrubbing operation as will hereinafter appear.

The gas scrubber GS also includes a water distributing manifold 30 adapted to be kept filled with water and having a slot 32 so that a curtain 34 of water falls therefrom as illustrated in FIGS. 1A, 2A and 10A when there is no flow of combustion gases through the gas scrubber. This curtain is broken up for an important reason which will hereinafter appear during operation of my incinerator.

An alternative embodiment of the scrubber is shown in FIGS. 10A and 11. As with the embodiment of FIG. 1A, the V-shaped scrubber chamber contains four rows of staggered scrubber elements. The chamber walls as seen in FIG. 11 diverge from front to back (the downstream direction), and may be, for instance between about 1½ to 2 times wider at the downstream end than at the upstream inlet end. The gap between adjacent impingement piers or scrubber elements, in the direction transverse to the direction of gases flow, in the first row is typically about 12 inches. In each subsequent row downstream the gap decreases, being typically 8 inches, 6 inches and for the last, or wringer row 3 inches, respectively. Thus the number of pillars is increased in each downstream row. A typical pillar is 12 inches in diameter and about 8 feet high; there is no space above or below the pillars for the gases to bypass thereby escaping scrubbing. The rows of pillars may be uniformly spaced in the downstream direction,

5 having for example a 9 inch gap between each row. Compared to prior art devices, the scrubber is very short; from the inlet end adjacent the bridge wall 204 as seen in FIG. 10A to the drop arch 205 the scrubber is typically about 9 feet long, but may be shorter or longer as requirements dictate.

The products of combustion, after leaving the gas scrubber GS, enter a plenum chamber 36 shown in FIGS. 2A, 10A and 11, and flow upwardly through the drying chamber DC, first passing through the deflecting or drying arch DA. The deflecting arch in the embodiment shown in FIG. 2A comprises a horizontal wall 38 of concrete, castable ceramic, or the like having reinforcing elements 40 therein and having a series of inclined passages 42 which serve to deflect the gases of combustion toward the sidewalls of the drying chamber DC. The drying chamber may have a vertical height approximately the same as shown for the plenum chamber 36 (portions having been broken away to conserve space on the drawing). At the top of the drying chamber DC, a blower 44 is provided suitably driven as by an electric motor 46. The blower has an intake chamber 48 and a discharge chamber or stack 50 to atmosphere.

In an alternate embodiment shown in FIGS. 10A and 11, 25 the deflecting arch is inclined from the horizontal with perpendicular holes therein to achieve the function of directing the gases against the drying chamber walls. In the drying chamber DC, water with fly ash entrained therein that has not been removed in the scrubber is wrung out or stripped from the gases by impingement against the sidewalls. The gases then pass through a pair of second, optional, deflecting arches 206 disposed in chambers 48, 48' on each side of stack 50. At this stage, little or no water will be wrung out, but some residual fly ash fines may stick to the walls by impingement thereon. The gases then pass out stack 50 via two fans 44 which are typically rated at 3 times the amount of air needed for combustion. The stack can be relatively short, and thus inexpensive, as compared to natural draft stacks, and is typically less than about 40 feet high.

As disclosed and claimed in the aforesaid copending divisional application, the grate means GM comprises perforated grates 52 and a means to support them so that they are reciprocably mounted. These grates may be formed of cast iron or the like with small holes drilled therethrough as shown in FIG. 1, and as shown in FIGS. 2, 5, 6 and 9 the grates rest on grate carriers 54 which are supported by a frame work of lateral and longitudinal I-beams 56 and 58, respectively. The I-beams 58 are supported by rollers 60 which in turn are journaled in stationary brackets on a partition 62 as shown in FIGS. 5 and 9 and a pair of shoulders 64 of the combustion chamber sidewalls 12.

The framework 56, 58 also carries five rows of rollers 68 to support longitudinal channels 66 which are secured at 70 to the front wall 16 as shown in FIG. 2 so that the framework can reciprocate beneath the channels but at the same time will support them. Surmounting the channels 66 are inverted channels 72 having side edges which are grooved as shown in FIG. 5 to coact with end flanges 74 of the grates 52 to effect a satisfactory seal for combustion purposes between the channels 72 and the grates. The inverted channels 72 have ratchet-like projections 76 having an important function for the burning refuse as will be described later. Reciprocations are imparted to the grate means GM by reciprocating the frame 56, 58 which has attached thereto three racks 78 as shown in FIGS. 2 and 9 meshing with pinions 80 on a shaft 82. A chain 84 operatively connects the shaft 82 to the output of a speed reducer 86 driven by a motor 88. The motor is under control of a projection 83 (shown in FIG. 1) which coacts with a pair of limit switches 85 and 87 to energize the motor for rotation in alternately opposite directions in a manner well known in the art, thus automatically reciprocating the grate means GM as long as current is supplied to the motor and controlled by the limit switches.

For supplying combustion air to the combustion chamber CC above the grate GM, blowers 90 are provided as shown in FIGS. 1 and 5 driven by motors 91 and supplying air to manifolds 92 extending along the sidewalls 12. A plurality of nozzles 94 extend from each manifold 92 into Venturi tubes 96 arranged at angles such as shown in order to furnish air for combustion in a direction downwardly from the side walls 12 and toward the center of the grate means GM.

Additional combustion air is supplied by a blower 98 driven by a motor 100 and discharging into a duct 102 having discharge openings 104 and 106 on opposite sides of the partition 62 as shown in FIG. 5 for supplying combination air beneath the grate means GM. The grate means is inclined to facilitate the movement of burning refuse therealong toward the dry ash conveyor AC and to effect a more even spreading and leveling out of the refuse and to effect distribution of combustion air through the grates 52 to the refuse. The downhill ends of the projections 76 are perforated as shown at 77 in FIGS. 5 and 6 to keep them relatively cool and promote more complete combustion of the refuse.

As will hereinafter appear, water containing fly ash flows downwardly along the inclined bottom wall 24a of the gas scrubber as shown in FIG. 2A and 10A into a trough 108. Discharge openings 110 lead therefrom into a sludge conveyor trough 112 containing the sludge conveyor SC (not shown in FIG. 10A). The trough 112 as shown in FIG. 3 and dotted in FIG. 2A leads to a sump 114 from which the water is pumped by a pump 116 driven by a motor 118, the intake of the pump being shown at 120. The trough 112 and the sump 114 thus constitute an open L-shaped settling tank from which water is drawn for recirculation to the gas scrubber. The pump and motor are contained in a compartment 122 sealed off from the tank 112, 114 and the pump has an outlet pipe 124 leading to the manifold 30. A baffle 126 serves as an aid to prevent the flow of sludge from the bottom of the trough 112 and the sump 114 into the intake 120.

In order to keep the water in the trough 112 and the sump 114 at a predetermined level 113 such as best shown in FIG. 2A, a water supply line 128 flows through a water meter 130 to a float valve 132 in a float chamber 134. The float chamber 134 has an outlet 136 leading into the sump 114. This arrangement provides make-up water to compensate for that which is evaporated by operation of the incinerator. In actual practice I find that a high water recovery is possible thus requiring only a nominal amount of make-up water and effecting a substantial economy in the use of water.

The ash conveyor AC as shown in FIG. 2 is adapted to receive dry ashes falling off the lower (right hand) end of the grate means GM which it will be noted is inclined downwardly toward the ash conveyor. The marginal right hand end of the grate means reciprocates as indicated by dot-and-dash lines over the ash conveyor so as to discharge ashes directly into the conveyor. As noted in FIG. 1, the major area of the grate means GM is provided with the perforated grates 52 whereas the left hand end under the inclined wall 20 and the right hand marginal end are provided with imperforate members 138 so that the burning of refuse is accomplished between the discharge end of the inclined wall 20 and the imperforate members 138 at the downhill end of the grate means. The imperforate members 138 just mentioned serve as a platform for the advance of ashes from the grates 52 and into the ash conveyor AC. As shown in FIG. 7, the ash conveyor at the right hand end has an upwardly and outwardly inclined portion 139 extending from the combustion chamber to discharge in an ash box 140 or the like and is driven by a chain 142 from the output shaft of a speed reducer 144 driven by a motor 146.

The sludge conveyor SC is somewhat similar in vertical cross section to the ash conveyor AC shown in FIG. 7,

being driven by a chain 148 (FIG. 3) from a speed reducer 150 which in turn is driven by an electric motor 152. The sludge conveyor discharges into a sludge box 154 or the sludge may be otherwise disposed of.

In the operation of my refuse incinerator, a truck load of refuse is dumped into the open end 13 of the combustion chamber CC and slides down the inclined wall 20 on to the imperforate members 138. Since a considerable portion of normal household and industrial waste and similar refuse consists of paper and other combustible materials, it can be readily ignited, and after suitable ignition, the blowers 44, 90 and 98 may have their motors energized for operation. The motor 88 may also be energized for reciprocating the grate means GM and the motors 146 and 152 may be energized for operating the ash conveyor AC and the sludge conveyor SC. The grate means GM is so designed as to hold and disturb the refuse for efficient aeration which results in faster and more complete burning when compared to burning on stationary grates.

The burning refuse produces products of combustion including fly ash and dry ashes. The dry ashes are gradually deposited in the ash conveyor AC due to the reciprocations of the grate means GM. The dry ashes are carried by the ash conveyor AC up the inclined portion 139 of the conveyor and into the ash box 140 or are otherwise disposed of.

Refuse is advanced along the grate means GM by reason of positional changes of the refuse relative to the grate accomplished during the backward portion of reciprocating grate motion. During the forward portion of grate motion a clear area of grate 138 becomes exposed from under the inclined wall 20 and is thereupon covered with incoming refuse. Accordingly as grate motion reverses the refuse now becomes positionally held by the inclined wall 20 while the grate slips beneath the refuse thereby effecting a change of position relative to the grate. The retarding effect of the inclined wall 20 is imparted through the refuse to all the burning material on the grate means, but not proportionally so. Heavier parts of the conglomerate refuse slip on the grate less due to greater friction, and lighter parts thereby flow around and past the heavier parts. Advancement of refuse along the grate is maintained as long as incoming refuse is sufficiently present on the inclined wall 20 to cover the free area exposed during forward grate motion.

Large variations in the rate of burning are inherent in the particle disorder of accumulated refuse with its varied physical geometry and material chemistry. It is to this situation that my grate is particularly adaptable. As refuse moves onto the grate, ignition of the refuse occurs on the inclined wall 20 due to kindling from slower moving parts of preceding quantities. The selectivity of movement to various particle weights becomes increasingly defined while movement progresses. As advancement of the burning particles continues, rates of burning are equated by combustion to changes in density to which the grate means is selective and thereby translates to rates of movement. The accuracy of translation is evidenced by a line of demarcation that defines the inert material toward the discharge end of the grate. In essence, rates of burning become rates of movement, and in such manner variables in the incineration of refuse are accommodated by the grate means as herein disclosed.

The foregoing described operation has the effect of breaking down the individual batches of refuse and substantially evenly distributing them over the grate means. Additional batches of refuse can be periodically fed to the incinerator to keep it in continuous operation. A major function of the projections 76 is to lift and disturb portions of the load during forward grate motion for more effective aeration and consequent burning.

The products of combustion including fly ash pass upwardly and over the baffle or bridge wall 18a as indicated by arrows in FIG. 2 and under the baffle 22 of FIG.

2A to the gas scrubber GS. The temperature generated in the combustion chamber may run as high as 1600° F. to 1800° F. and the velocity of the products of combustion and fly ash from the outlet end of the combustion chamber may be in the range of 1000 f.p.m. to 3000 f.p.m. caused by the operation of the blowers 44, 90 and 98. Such high velocity is desirable in order to effectively wet the surfaces of the piers 28 with water from the curtain of water 34 which, of course, is distorted from the showing in FIG. 2A when the blowers are in operation. I have found that the water effectively wets the surfaces of the piers 28 so most of the fly ash will be collected in the water that gravitates downwardly along the piers and flows downhill along the gas scrubber chamber floor 24a and into the trough 108. The water also has the effect of keeping the piers 28 cool relative to the transit gases of combustion by thermal sink losses and vaporization of the water.

As noted above, the second high temperature zone 207 between the bridge wall 18a and the inlet of the scrubber permits some secondary combustion, but is not a settling chamber. In prior art settling chambers the gases speed was on the order of 1-9 feet/second, the slow speed permitting ash to settle out. However, in the present invention, a settling chamber per se may be omitted because of the high efficiency of the scrubber and dryer. In the second zone 207, the gases speed is above 9 feet/second, and may be as high as 30-40 feet/second. In moist climates, the speed may be as low as 10-12 feet/second; in the Mid-West the value may be 18-26 feet/second and in more arid climates may be about 30 feet/second. In all areas the speed depends on the moisture content of the refuse.

The size of the second high temperature area or chamber 207 is in inverse proportion to the gases speed: smaller for higher gases speed. In contrast to prior art, secondary chambers which operate as settling chambers and which are typically three times larger than the primary combustion chambers, the chamber 207 of my invention is typically smaller, and may be as little as 1/3 the combustion chamber CC size, for an equal capacity incinerator.

The spacing between the piers is such as to reduce the area through which the products of combustion pass as they flow through the gas scrubber so that an even higher velocity is attained in the gas scrubber (on the order of 3000 to 9000 f.p.m.). Due to the increase in velocity of the products of combustion through the gas scrubber, as well as the presence of water therein as films on the piers 28 and the cooling effect of the water as it evaporates, the temperature is only about 200° to 250° F. around the piers. The piers themselves do not get above about 212° F. in normal operation. The velocity is then reduced again in the drying chamber DC so that the temperature is increased to about 300-400° F. thus increasing the drying effect and making for a gas scrubber and gas dryer combination having a high overall efficiency.

By staggering the piers as shown in FIGS. 1A and 11, the flow past the first row impinges the second row and the flow past the second row impinges the third row and so on, in such manner as to effectively accomplish maximum collection of fly ash. These piers are formed preferably of water-resistant ceramic capable of withstanding high temperature on the order encountered in the gas scrubber and to withstand the abrasive effect of the fly ash impinging against them. A preferred pier material is a castable refractory having high strength, low iron content and good abrasion resistance. A commercially available type is "AR-153 Castable" made by Walsh Refractory Co. of St. Louis. Concrete will work for a short period of time but it is not preferred; a castable refractory has an estimated lifetime of 3-5 years. To increase pier strength and abrasion resistance, up to 50% by weight alumina can be added to the castable refractory.

Although I do not wish to be bound by theory, it is important that the piers have a high water retention charac-

teristic, i.e., relatively surface porous, and have a high abrasion resistance characteristic. The porous impingement scrubber piers absorb water from the surface inwardly, and the surfaces are kept continuously wetted. Thus the water evaporates to form steam from the action of hot gases and the piers are protected by the collar of steam thus formed, by the evaporation, and by the absorbed water.

As for the arrangement of the piers 28 in rows in the gas scrubber GS, the first row of piers has as one effect, the reduction of the temperature of the products of combustion. The second row, being offset relative to the piers of the first row, collects fly ash impinging on their water films so as to be entrained in the water that gravitates downwardly along the piers. Likewise the third and fourth rows, being offset also collect ash. The piers obviously act as retarders for the products of combustion to effect separation of fly ash therefrom. The third row serves, inter alia, as a final wash for the removal of most of the residual fly ash from the first and second row, and the fourth row acts as an impingement wringer. By the time the products of combustion pass the fourth row, up to 95% of the fly ash has been removed. Slugs of water from the curtain 34 act as lubricant for the fly ash thus reducing wear on the piers.

As compared to prior art spray chambers, the scrubber of this invention operates far more efficiently and effectively because the gases must act against the continuous discharge of the curtain of water. Prior art spray nozzles break up water into very fine droplets or mist-like particles, which evaporate in the gases in molecular form. This is particularly true in incinerators having high gases temperatures. But the evaporated water cannot trap the fly ash and thus unacceptable levels of dust and ash pass out the stack. Although I do not wish to be bound by theory, in my invention the gases impinge on the curtain of water and force it against the scrubber piers. In impinging on the curtain, the ash entrained in the gases is trapped by the water and retained in relatively large droplets until they impinge on the piers. It is principally at the piers that the water is broken up into fine droplets leaving the ash to be washed down the pier faces by the excess water, and pass along the floor into trough 108. Thus, the gases lose kinetic energy by impingement against the water curtain. The rate of heat exchange is relatively low and the droplets large. Since the distance between the curtain and piers is small, on the order of 2-3 feet, and the gases velocity large, the drops with the captive ash do not have time to evaporate before being immediately impacted against the piers. Sprays of water cool the gases, but do not effectively trap or retain the ash. In my invention the weight of the water is used to advantage.

Because of the effectiveness of the water curtain and its relationship to the piers in trapping and retaining products entrained in the gases as compared to sprays, the scrubber can be used to advantage in low temperature operations such as removal of industrial vapors from exhaust gases, the trapping of SO₂ in the production of sulfuric acid, and the like. Where desired, the scrubber and dryer of my invention can be used with a conventional incinerator having a settling chamber.

The relatively clean products of combustion and some water entrained therewith are discharged from the gas scrubber GS into the plenum chamber 36 which acts as a breaching or expansion chamber. The gases then flow upwardly through the deflection arch DA and into the drying chamber DC. The passageways 42 of the deflection arch, being inclined as they are, direct the products and water towards the walls of the drying chamber as illustrated by arrows in FIG. 2A and the impingement of the water against these walls results in a drying action by reason of such water trickling down the walls of the plenum chamber and eventually into the trough 108. Accordingly, products of combustion almost entirely free of fly ash are discharged into the inlet 48 and through the

blower 44 and its outlet 50 to atmosphere thus producing a "clean burning" refuse incinerator satisfactory for the requirements of most smoke ordinances. In the embodiment of FIGS. 10A and 11 there are a plurality of impingement walls 208, 209, 210, 211, and 212.

The fly ash and water draining from the gas scrubber into the trough 108 drains through the discharge openings 110 into the sludge conveyor trough 112 and the sludge settles to the bottom of the trough whereby it may be picked up by the lower stretch of blades of the sludge conveyor SC and pushed along the trough 112 toward the right and then up the inclined portion 139 and into the sludge box 154. Excess water drains back into the trough 112 and finds its way into the sump 114 where the water can be recirculated to the manifold 30 and the slot 32 to effect an economy of operation represented by a considerable saving of water as distinguished from those types of gas scrubbers which use fresh water throughout their operation without recirculation. Some of the water, however, will evaporate because of the heat generated in the incinerator and this is automatically compensated for by operation of the float valve 132 which may be set to replenish the water to the level 113 shown in FIG. 2A. About 80 g.p.m. are added with an estimated loss of 15 g.p.m. to the wet sludge. The estimated remainder of 65 g.p.m. is exhausted as water vapor from the stack.

The following examples will illustrate one or more of the several embodiments of this invention.

Example 1.—Prior art

For comparative purposes, this example describes a conventional incinerator operation. The incinerator of this example has two cells or primary combustion chambers rated to operate at a total of 400 tons per day. Each of the two side-by-side cells is on the order of about 9½ feet wide by 10 feet high and some 33 feet long. The two cells open at the downstream end into a fly ash settling chamber which is on the order of 12 feet wide by 27 feet high and 35 feet long, with the long axis of this settling chamber being set transverse to the long axis of the two side-by-side cells. This chamber also operates as a secondary combustion zone or flame space. The downstream side of the settling chamber, near an offset end, opens into a dual-zone ash removal chamber. In this chamber there is a first dry zone that is about 12 feet wide by 15 feet high and 10 feet long where more ash settles out. From the first dry zone the gases and fly ash thence pass through a cathedral wall or archway and proceed into a wet zone. This zone is a spray chamber 12 feet wide, 15 feet high and 18 feet long having recessed ceiling and wall sprays. These operate to give both vertical and horizontal sprays of water at the rate of about 100 gallons per minute to remove some fly ash. From the spray chamber, the gases pass via a short passageway into a 150 foot smoke stack. Pieces of charred paper the size of the palm of a hand were exhausted from the stack, and thus the output of the smoke stack was quantitatively estimated at being well above the permissible dust loading as defined above, 0.85 lbs. of dust per 1000 lbs. of flue gas. Although the two-cell plant was rated at 400 tons/day, it operated well below that value, at an estimated 300 to 350 tons/day. In addition to the disadvantages of dust loading, the charred paper, and the large and expensive stack, both the ceiling and the wall sprayers, although they were recessed, continuously burned out and became clogged.

Example 1A.—Prior art

To improve the capacity of the above type of incinerator, a conventional Schneible dual-silo collector was installed to take part of the load from the incinerator. A model F-21C "Multi-Wash Collector" made by the Schneible Company of Detroit, Mich., was attached via suitable duct work to the settling chamber of the inciner-

ator described in Example 1. Such a conventional Schneible collector operates by introducing, under force draft, dust, fumes or vapors tangentially through an inlet at the bottom of the silo. The conical bottom creates a vortex which sends the air upwards in a spiralling motion. A washing agent is introduced at no head pressure just below the entrainment separator and the water cascades downwardly evenly over plates carrying collected material to the slurry outlet. The basic Schneible silo costs about \$70,000 including \$6,500 for an associated settling tank; some of that cost was for concrete foundations. In addition, over 40 feet of duct work costing about \$11,000 and a fan costing about \$10,000 was required. This installation also required a separate stack, 32 feet high

The use of the Schneible multi-wash collectors, operating simultaneously in parallel with the original dual-zone ash removal chamber described above in Example 1, raised the capacity to about 450-500 tons/day when operating. However, the permissible duct loading of 0.85 lbs. of dust per 1000 lbs. of flue gas was not achieved, it being estimated that the dust loading was well in excess of that permissible figure. As with the original dual-zone ash removal chamber of the incinerator described above in Example 1, the output from the Schneible stack included charred pieces of paper the size of the palm of one's hand.

In addition, the metal Schneible units had an extremely short life-time because of the acids formed during the washing of the incinerator combustion product gases and the abrasion of parts. The silos were eaten and abraded through within five weeks and the unit leaked in numerous places. The entire unit was shut down about 50% of the time for repairs and cleaning. Each time the unit was shut down, the plant capacity dropped back to the original below-rated level. Hydrated lime in the wash water was tried but the amounts necessary for neutralization was prohibitively expensive and caused severe clogging. Within 9 months, of which the unit was down half that, the unit became unrepairable. Of the original total cost of \$89,000 about \$60,000 was unrecoverable, and represents the cost (but not the operating and repair expenses) of the unit that operated unsatisfactorily for only about 4½ months' effective life.

Example 2

45

The Schneible unit of Example 1A was replaced with an embodiment of the scrubber and dryer of the present invention. As with the Schneible collector, this unit operated in parallel with the spray-type scrubber of the original plant. The fan and 32 foot stack of the Schneible device was salvaged and coupled to the scrubber and drying chamber of the present invention, substantially that shown in the embodiment of FIGS. 1A, 2A and 3. The output of the two-celled incinerator plant above described rose to from 550 to 600 tons/day. This was an improvement of from 250-300 tons/day over the original actual output of the plant, and an increase of 100-150 tons/day over the output shown in Example 1A, where the Schneible collectors were used in conjunction with the original plant having the spray chamber. It was estimated that about ½ of the entire plant output was taken through the scrubber-dryer of this invention. It was observed that the dust loading of the discharge from the stack connected to the scrubber-dryer of this invention appeared to be below the permissible level, and there was no large pieces of fly ash exhausting therefrom. No hydrated lime for acid neutralization was required, and no frequent downtime, with an attendant loss of capacity, for cleaning and repair was necessary.

Example 3

This illustrates the operation of an entire incinerator plant utilizing the V-shaped chamber scrubber substantially as shown in the embodiment of FIGS. 10A and 11 and having a dryer as shown in FIG. 2A. The plant is

rated at 300 tons/day and consists of two 150 ton/day cells. The refuse, after being weighed, is received at the plant at a dumping area and is pushed onto an inclined pan conveyor which feeds the incinerator units as shown in FIG. 10. The refuse falls by gravity down the short inclined refractory hearth 20 onto a reciprocating grate system such as is disclosed and claimed in my copending divisional application Ser. No. 648,845, filed Nov. 9, 1967. The combustion chamber CC is equipped with overfire air nozzles for the introduction of secondary combustion air. A force draft fan is provided for each furnace. The combustion gases pass from the furnace over a bridge wall and below a drop curtain at relatively high velocities into the secondary high temperature zone which operates as a secondary combustion zone, but no ash settling takes place. Then the gases enter the scrubber system of this invention. The scrubber system is that described above with reference to FIGS. 10A and 11. Water is recirculated at the rate of 500 gallons/min., with make-up water being introduced at 80 gallons/min. The curtain of water is formed by a slot opening across the full width of the inlet to the scrubber section. The water depth in the roof trough is enough to insure a 1 to 2 inch deep continuous water flow into the slot. The cleaned gases pass into the expansion or dewatering section and thence through the deflection arch to impinge on the walls of the drying chamber. This section further serves as an entrainment separator preceding the induced draft fan with the gases being taken off above the water. Constant speed ID fans serve each incinerator unit with adjustable dampers serving as air induction openings in the ID inlet plenum to regulate the furnace draft. The fans discharge into a plenum section which serves as the bottom inlet of the refractory lined steel stack. The gases are discharged from the stack approximately 32-35 feet above the grade area at the rear of the plant.

Emission tests were conducted at this plant and were performed in accordance with the requirements of the A.S.M.E. Test Codes PTC 21-1941 Dust Separating Apparatus, and PTC 27-1957 Determining The Dust Concentration in a Gas Stream, and the Informative Report No. 2 of the Air Pollution Control Association Incinerator Committee titled "Test Methods for Determining Emission Characteristics of Incinerators" by F. R. Rehm. Pursuant to the 3 codes and the study, the tests were carried out to satisfy the four basic requirements, which are:

- (1) Securing a truly representative sample of the gases and suspensoids;
- (2) Filtering and weighing the particulates in the sample gas stream;
- (3) Measuring the sampled gas volume;
- (4) Making other supplementary measurements of temperature, pressure, gas density, gas consumption, gas molecular weight, excess air levels, needed to compute dust loading.

In addition to the dust loading tests, volumetric determinations were conducted on each unit. The visual appearance and the odorous nature of the stack effluents were regularly assessed throughout each dust loading test run. As part of the dust loading test, a continuous check was made of the excess air levels of the exhaust effluents. The sampled particulates from the dust loading test were subjected to laboratory analyses. With the stack velocities encountered at this plant on the day of testing, it can be anticipated that the maximum cumulative test error (sampling, weighing, volumetric, etc.) would approach plus or minus 9%. Every precaution and effort was made to minimize any unnecessary test error.

The results of the stack dust loading emission rates are summarized in Table I below and are presented on the basis of commonly used dust loading limitations. This table presents the results on an actual gas basis. Runs 1-3 were on the No. 1 Incinerator cell; Runs 4-6 on the No. 2 cell.

TABLE I.—STACK EXIT DUST LOADINGS (ACTUAL)

5	Test Run	Corrected to 12% CO ₂ basis		Corrected to 50% excess air basis	
		Grains/ft. ³ *	Lbs. dust/1,000 No. Gas	Grains/ft. ³ *	Lbs. dust/1,000 No. Gas
1	1	0.317	0.586	0.253	0.470
2	2	0.253	0.472	0.200	0.373
3	3	0.230	0.425	0.187	0.344
4	4	0.179	0.344	0.142	0.264
5	5	0.183	0.339	0.140	0.261
6	6	0.202	0.376	0.155	0.290

*SCTP: 32° F., 29.92 in. Hg.

The following Table II summarizes the test results expressed on the less commonly used *dry* standard cubic foot per minute basis. Standard conditions are sometimes defined as 32° F. and 29.92 in. Hg., and sometimes as 60° F. and 29.92 in. Hg.

TABLE II.—STACK EXIT DUST LOADINGS (DRY)

20	Test Run	Corrected to 12% CO ₂		Corrected to 50% Excess Air	
		Grains/dry ft. ³ *	Grains/dry ft. ³ *	Grains/dry ft. ³ †	Grains/dry ft. ³ †
1	1	0.366	0.293	0.277	
2	2	0.297	0.235	0.222	
3	3	0.262	0.213	0.202	
4	4	0.208	0.165	0.156	
5	5	0.221	0.169	0.160	
6	6	0.243	0.187	0.177	

*SCTP: 32° F., 29.92 in. Hg.

†SCTP: 60° F., 29.92 in. Hg.

The above table shows that the performance of the No. 2 incinerator unit consistently conformed to the requirement of 0.20 grain/dry standard cubic foot (defined at either 32° F. or 60° F.), corrected to a 50% excess air basis, which has been incorporated in a number of the more recently enacted air pollution ordinances. The last two test runs on the No. 1 incinerator unit met this same requirement (60° F.) within the inherent error of the test determination.

The average exit flue gas dust loading of the three tests run on the No. 1 incinerator cell, while burning a residential or domestic refuse at, or in excess of, rated burning capacity and with scrubber water rates as outlined above was 0.396 lb. dust/1000 lbs. flue gas, corrected to a 50% excess air basis. This average exit dust loading is

$$\frac{0.85 - 0.396}{0.85} \times 100 = 53.4\%$$

below the commonly used exit flue gas dust loading limitation of 0.85 lb. dust/1000 lbs. flue gas, corrected to a 50% excess air basis. This data shows that the No. 1 incinerator cell exhibited very good particulate emission performance.

The average exit flue gas dust loading of the three tests run on the No. 2 incinerator cell while operating at rated burning capacity burning various combinations of commercial and domestic refuse and with scrubber water rates as detailed above was 0.272 lb. dust/1000 lbs. flue gas, corrected to a 50% excess air basis. This average exit dust loading is

$$\frac{0.85 - 0.272}{0.85} \times 100 = 68.0\%$$

below the commonly used exit flue gas dust loading limitation of 0.85 lb. dust/1000 lbs. flue gas corrected to a 50% excess air basis. This data shows the No. 2 incinerator cell also has excellent particulate emission performance.

The following Table III was developed utilizing the dust loading test results reported above for cell No. 2, and additional volumetric data in accordance with the

15

tests, including accurate weighing of the refuse charge, as follows:

TABLE III.—STACK MASS EMISSION RATE

Test run	Incinerator	Lbs./min.	Lbs./hour	Lbs./ton of Charge ¹
4-----	2	0.222	13.32	2.13
5-----	2	0.223	13.40	2.14
6-----	2	0.252	15.12	2.42

¹ 6.25 tons/hour/unit (rated capacity).

The above Table III shows that the emission rate for the No. 2 incinerator cell ranged from 13.2 to 15.12 lbs. dust/hour. The No. 2 cell operation is reasonably representative of the operation of the invention.

Visual emissions

The Ringelmann Chart published by the U.S. Bureau of Mines is the most usually accepted standard upon which visual smoke emission limitations are based. The Ringelmann Chart consists of a series of cross-hatched black lines of various widths printed on a white background. The lines are to be viewed at a distance sufficiently far to give a blended gray color with the white background. Ringelmann numbers range from No. 0.0R for a completely white smoke or visual discharge to a No. 5.0R density for a solid black emission. A No. 1.0R would be a 20% dense black smoke, a No. 2.0R a 40% dense black smoke, etc. The Ringelmann Chart has been printed only on a black and white basis with gradations being various shades of gray. To describe visual emissions that are other colors or shades, an "opacity" measuring device or scheme was devised. The opacity of a visual emission is related to the ability to "see through" the visual plume and is rated on an "equivalent Ringelmann Number" basis. All visual readings of stack effluents suffer from various influences such as the difference between individuals' eyesight, the viewing location, the background against which the plume is assessed, the thickness of the plume, etc. Despite the vagaries in assigning a Ringelmann Number of an "equivalent Ringelmann Number" to visual emissions, this is the method used almost exclusively in all air pollution control ordinances to measure permissible emission levels. Practically all air pollution control ordinances make provision for some period of emission of No. 2.0 Ringelmann smoke. Most air pollution ordinances prohibit visual emissions greater than No. 2.0 Ringelmann density except for certain operating conditions for which limited amounts of such emissions are permitted. The assessment of visual emissions having a relatively high moisture content must be done carefully since it is at best a difficult determination.

The visual stack emission readings were recorded at regular intervals throughout each dust loading test run. The results of the visual emission observations are summarized in Table IV below:

TABLE IV.—VISUAL EMISSIONS, NUMBER OF READINGS, "EQUIVALENT" RINGELMANN NUMBER

Test run	0.0 R	0.5 R	1.0 R	1.5 R	2.0 R	3.0 R	4.0 R	5.0 R
1-----	14	14	2	-----	12	-----	-----	-----
2-----	15	10	1	2	12	-----	-----	-----
3-----	21	9	-----	-----	-----	-----	-----	-----
4-----	21	7	2	-----	-----	-----	-----	-----
5-----	17	13	-----	-----	-----	-----	-----	-----
6-----	19	10	0	1	-----	-----	-----	-----

¹ 10 sec. each.

From the above table, it can be seen that only during Dust Test Run No. 2 was smoke of an opacity or density as great as an "equivalent" Ringelmann No. 2.0 observed. This visual emission performance is well within the most stringent visual emission limitations being enforced in this country today. On two occasions during Dust Test Run No. 2, visual emissions of 10 seconds durations of an opacity of Ringelmann No. 2.0 were observed. In Dust Test Runs No. 1, No. 3, No. 4 and No. 5, no visual emissions were observed that were greater than a Ringelmann No. 1.0 density. In Dust Test Run No. 6, one reading of

16

Ringelmann No. 1.5 density was observed. It is clear from the above data that the above incinerator units do not present any visual smoke emission performance problems when operated at, or slightly in excess of rated burning capacity.

It should be noted that with the water vapor content of the stack gases (12.35% to 17.38%), there was a dense white vapor plume formed as this water vapor condensed in the cool outside ambient air on these dates. This white vapor plume should not be confused with visual smoke emissions. The white water vapor plume forms approximately 10-20 feet above the point of stack discharge. The exhaust gases can be seen to be virtually clear below this point.

15 From the foregoing specification, it will be obvious that I have provided a refuse incinerator and a method of treating refuse which accomplish the objects set forth in the foregoing specification. An incinerator is disclosed which does not need a high chimney to create draft as 20 in many installations where the chimney alone may cost as much as \$125,000. In many prior art refuse incinerators the cost of blowers is also high because they must withstand considerable abrasive action by fly ash whereas in my installation the blower 44 can be of a relatively inexpensive type since the products of combustion passing 25 therethrough are relatively free of fly ash.

My apparatus and method contribute to minimization of air pollution as the output from my incinerator is about 90% to 95% cleaner than the output from conventional 30 chimney, caused, of course, by the removal of a greater proportion of fly ash in the efficient gas scrubber disclosed. As far as complete refuse incinerator systems of comparable size are concerned, those with stacks or chimneys may cost three times as much as an installation of 35 the kind herein disclosed.

Some changes may be made in the construction and arrangement of the parts of my incinerator, and my method steps may be varied to some extent without departing from the real spirit and purpose of my invention, 40 and it is my intention to cover by my claims any modified forms of structure, use of mechanical equivalents or modification of the method steps disclosed which may reasonably be included within their scope.

45 I claim as my invention:

1. In an incinerator comprising a primary combustion chamber, a secondary combustion chamber and fly ash removal means, the improvement in said fly ash removal means which comprises:

50 means defining a scrubber chamber having an inlet and outlet,
means defining scrubber elements disposed in said chamber, said elements having a relatively porous surface adapted to absorb water therein,
means for supplying water to the top of said scrubber chamber inlet,
means for directing said water in the form of a continuous curtain across the width of said chamber, said directing means being disposed at the top of the inlet end of said chamber and immediately upstream from said elements, whereby fly ash entrained in gaseous products of combustion impinge on and are trapped by said water and said water is carried by said gaseous products of combustion downstream to immediately impinge on said scrubber elements,

60 means for producing a high velocity flow of gaseous products of combustion from said primary combustion chamber through said scrubber chamber, said flow means being disposed in communication with said scrubber chamber outlet, and
means for removing from said scrubber chamber the water draining from said scrubber elements and the fly ash entrained therewith.

70 2. An improved incinerator as in claim 1 which includes a drying chamber disposed between said scrubber

chamber and said flow producing means, said drying chamber comprising side walls and means for deflecting said gaseous products and water carried thereby toward said side walls to forcibly impinge thereon, whereby said water and residual fly ash entrained therewith are separated therefrom before entering said flow producing means, said means for deflecting comprising a passageway in said drying chamber, and a cross wall therein at an angle to the path of gas flow through said passageway and having passages therethrough.

3. An improved incinerator as in claim 2 wherein said passages therethrough are oriented substantially normal to the plane of said cross wall.

4. An improved incinerator as in claim 2 wherein said water removing means includes a sludge conveyor having a horizontal portion disposed to receive water and fly ash entrained therewith from said scrubber elements and from said drying chamber and being operable to remove sludge from said water, and having an inclined portion to elevate the sludge above the level of the water and discharge it from the incinerator.

5. An improved incinerator as in claim 1 wherein said scrubber elements comprise a plurality of staggered rows of castable refractory impingement piers oriented vertically and thereby substantially parallel to the flow of said curtain of water, said piers being also oriented normal to the path of flow of said products of combustion.

6. An improved incinerator as in claim 5 wherein said piers are arranged in spaced rows across said scrubber chamber with the spacing in each row less than the preceding upstream row.

7. An improved incinerator as in claim 6 wherein said piers are spaced and of such dimension that the area through which said gaseous products pass is reduced to about one-third the area of said scrubber chamber.

8. An improved incinerator as in claim 1 wherein said means for supplying water includes means for recirculating water from said removing means to said inlet end of said scrubber, a manifold for receiving said recirculated water, said manifold having a slot transverse of said scrubber inlet through which said water falls, said slot being disposed at said inlet immediately upstream of said scrubber elements, and float-controlled means for supplying make-up water to compensate for vaporization of water during operation of said scrubber.

9. An improved incinerator as in claim 1 wherein said scrubber chamber widens from inlet to outlet and said scrubber elements are arranged in rows crosswise of said scrubber chamber with a series of spaced scrubber elements in each row with the spacing in each row progressively reduced in a downstream direction.

10. An improved incinerator as in claim 9 wherein said scrubber elements comprise a plurality of staggered rows of castable refractory impingement piers, the number of piers in each succeeding downstream row increasing.

11. A scrubber suitable for removing entrained vaporous or particulate material from gases comprising:

means defining a scrubber chamber having an inlet and outlet,

means defining scrubber elements disposed in said chamber, said elements having a relatively porous surface adapted to absorb water therein, and being arranged in a plurality of rows with a spaced series thereof in each row and an increasing number of elements in successive rows, the spacing between elements in each row decreasing in successive rows,

means for supplying water to the top of said scrubber chamber inlet,

means for directing said water in the form of a continuous vertical curtain across the width of said chamber and said scrubber elements being vertical and thereby parallel to such curtain of water, said directing means being disposed at the top of the inlet end of said chamber and immediately upstream from said elements, whereby said material entrained

in said gases impinges on and is trapped by said water, and said water is carried by said gases downstream to immediately impinge on said scrubber elements,

means for producing a high velocity flow of gases through said scrubber chamber, said flow means being disposed in communication with said scrubber chamber outlet, and

means for removing from said scrubber chamber the water draining from said scrubber elements and the material entrained therewith.

12. A scrubber as in claim 11 which includes a drying chamber disposed between said scrubber chamber and said flow producing means, said drying chamber comprising side walls and means for deflecting said gases and water carried thereby toward said side walls to forcibly impinge thereon, whereby said water and residual entrained material therewith are separated therefrom before entering said flow producing means.

13. A scrubber as in claim 11 wherein said scrubber elements comprise a plurality of staggered rows of castable refractory impingement piers oriented perpendicular to the path of flow of said products of combustion.

14. A scrubber as in claim 11 wherein said scrubber chamber increases in width downstream relative to the flow of gases therethrough.

15. A scrubber suitable for removing entrained vaporous or particulate material from gases comprising:

means defining a scrubber chamber having an inlet and outlet,

means defining scrubber elements disposed in said chamber, said elements having a relatively porous surface whereby water is absorbed therein,

means for supplying water to the top of said scrubber chamber inlet,

means for directing said water in the form of a continuous curtain across the width of said chamber, said directing means being disposed at the top of the inlet end of said chamber and upstream from said elements, whereby said material entrained in said gases impinges on and is trapped by said water, and said water is carried by said gases downstream to immediately impinge on said scrubber elements,

means for producing a high velocity flow of gases through said scrubber chamber, said flow means being disposed in communication with said scrubber chamber outlet,

means for removing from said scrubber chamber water draining from said scrubber elements and the material entrained therewith, said scrubber including a drying chamber disposed between said scrubber chamber and said flow producing means, said drying

chamber comprising side walls and means for deflecting said gases and water carried thereby towards said side walls to forcibly impinge thereon, whereby said water and residual entrained material therewith are separated therefrom before entering said flow producing means, said scrubber elements comprising a plurality of staggered rows of castable refractory impingement piers oriented vertically and perpendicular to the path of said products of combustion,

and said means for supplying water including

means for recirculating water from said removing means to said inlet end of said scrubber, a manifold for receiving said recirculated water,

said manifold having a slot transverse of said scrubber inlet through which said water falls,

said slot being disposed at said inlet upstream of said scrubber elements, and float-controlled

means for supplying make-up water to compensate for vaporization of water during operation of said scrubber.

16. A method of removing particulate matter entrained in gases flowing from an incinerator comprising

forming a continuous curtain of water, passing said gases at high velocity into contact with said curtain whereby said particulate matter is trapped thereby and said water is carried downstream by said gases in relatively large droplets, substantially immediately and progressively constricting the area of passage of said gases and water droplets through a plurality of piers adapted to absorb water whereby the velocity of said gases is increased and said droplets having particulate matter trapped therein are collected, deflecting said gases whereby a substantial amount of water is removed therefrom, removing said water having particulate matter trapped therein, and discharging said gases as flue gases, whereby said discharged flue gases are substantially free of particulate matter.

17. A method as in claim 16 wherein said gases are gaseous incinerator combustion products having fly ash entrained therein as said particulate matter, and said flue gases are discharged sufficiently free of fly ash to be below 0.85 lb. dust/1000 lbs. of flue gas based on 50% excess air.

18. A method as in claim 17 which includes the steps of removing fly ash in the form of sludge from said removed water, recirculating said water to provide water for said curtain, and adding make-up water to compensate for evaporation loss.

19. A method as in claim 17 wherein said gaseous incinerator combustion products prior to passing through said water curtain have a temperature of up to about 1800° F. and a velocity of between about 1000 to 3000

f.p.m., the amount of said restriction is such as to raise the velocity of said combustion products by about three-fold, the amount of water in said curtain is controlled to entrain up to about 95% of said fly ash in said water and to reduce the temperature of said gaseous products during said constricting step to below about 250° F., and the velocity of said gaseous products is reduced and the temperature raised during said subsequent deflecting step.

UNITED STATES PATENT OFFICE
CERTIFICATE OF CORRECTION

Patent No. 3,447,287 Dated June 3, 1969

Inventor(s) L. H. Andersen

It is certified that error appears in the above-identified patent and that said Letters Patent are hereby corrected as shown below:

Figure 2A, element "14a" should read --14b--.

Column 4, line 36, "FIG. 1" should be --FIG. 2--.

Column 14, line 5, "No." should be --Lbs.---.
